METHOD AND DOUBLE STOCKING BLANK FOR MANUFACTURING STOCKINGS

Filed Feb. 25, 1931

UNITED STATES PATENT OFFICE

1,942,331

METHOD AND DOUBLE STOCKING BLANK
FOR MANUFACTURING STOCKINGS

James L. Getaz, Maryville, Tenn.

Application February 25, 1931. Serial No. 518,231

17 Claims. (Cl. 66—183)

This invention relates to the knitting of hosiery and more particularly to the knitting of hosiery on seamless knitting machines and it is an object of this invention to provide a method by which stockings having all the advantages of full fashioned stockings can be knit on circular knitting machines. It is also an object of this invention to provide a method by which a blank from which two fashioned stockings can be obtained can be knit on a circular knitting machine. It is also an object of this invention to provide a blank knit on a circular knitting machine in which the leg portions of two stockings are knit side by side and the toe of one stocking is arranged toward the top of the other stocking.

In the drawing—

Figure 1 is a plan view of the blank showing the arrangement of the two stockings therein and showing in dotted lines the formed stocking feet.

Fig. 2 is a diagrammatic view showing the relative positions of the needle segments used in forming the toe pockets and heel tabs at opposite sides of the blank tube.

Fig. 3 is a fragmentary view drawn to a larger scale in the region of a heel;

Fig. 4 is a section on the line 4—4 of Fig. 3;

Fig. 5 is a fragmentary view drawn to a larger scale in the region of a toe; and

Fig. 6 is a section on the line 6—6 of Figure 5.

In the drawing the blank is shown as comprising a knitted tube for forming two oppositely arranged stockings A and A' having the welts or tops W, W', the leg portions B, B' which are joined together along the lines C on opposite sides of the tube and the feet D, D' which comprise the insteps 2, 2' separated from the legs of the other stockings on each side by sole portions 4, 4' which may be reinforced. Toe pockets 6, 6', high splice heel portions 8, 8' and heel portions or heel tabs 12, 12' are also provided. In place of forming the heel portions or heel tabs and toe pockets as folds attached to the tube as the blank is formed the heel and toe portions can be formed on a separate machine and attached in the usual way after the stockings have been separated.

In the manufacture of the blank a seamless knitting machine of rather large diameter, of from 5" to 6", is employed to produce a tubular blank from which two stockings can be made from each length or blank, each blank being shorter than the combined length of two stockings. The maximum width of the tube is available for extra wide ends of the welt. As shown

in the drawing, the toe of each stocking is adjacent the welt of the other stocking but it is to be understood this invention is not to be limited to the relative positions shown as the blank may be lengthened and the stocking feet brought closer together, the relative positions of the two stockings in the blank being otherwise as shown.

In manufacturing the blanks, assuming the machine used is a circular knitting machine of a well known type as a Scott & Williams circular knitting machine, the knitting is started on all needles and the entire welt at one end as welt W of stocking A is knit on the full circumference of the machine and the stitches on the transfer bits are transferred to the needles for

the completion of the welt, in case an automatic welt machine is used. If an automatic welt machine is not used the welt will be turned and sewn after the blank is removed from the machine but it will be noted that the welts at each

end of the blank will be made in the same manner. It will also be noted that in this fashioned stocking no matter how the welt is made, the welt will be cut on a bias from the maximum width of the fabric at the point where the welt is folded over to approximately two thirds the width of the fabric at the point where the welt W joins the leg B so as to bring the welt to the proper size and taper. While the triangular piece 10' thus left over is eventually discarded, it is useful in the knitting of the blank in starting the knitting of the toe pocket 6' as a substitute for loopers rounds. All the needles of

that portion of the circumference which are used for the leg portion B of the stocking A whose welt has thus been made, are then thrown out of action and with them half of the remaining needles which are to be used on the foot D' of the other stocking A'. The needles which are to be used for the foot portion B' which are

put out at this point are the needles to be used in forming the sole portions 4'. With the remaining needles a seamless toe pocket 6', that is, a narrowed and widened toe, is knit in the usual way with the portion 10' of the top W serving in place of the usual looping or starting courses. The toe is afterwards completed or

closed in the usual manner. After the toe pocket 6' has been knit the segments of needles for knitting the sole portions 4' at each end of the toe pocket segment are thrown back into action and with them is thrown the segment of needles for the leg B of the stocking A. The knitting then proceeds in a round and round manner and

where the sole portions 4' are to be reinforced.

reinforcements are introduced into the stocking B', the knitting of the leg B of the stocking A proceeding simultaneously with the knitting of the foot D' of the stocking A'. The reinforcing yarns for the portions 4' when used will be floated across the cylinder on both sides and they will provide two straight pieces of reinforcement in each course. Forming the sole portions 4' adjacent the leg B of the stocking A 5 brings the sole portions 4' at the back of the stockings and causes the wales on the front of the stocking to be straight up and down. The toe pocket 6', formed in the manner described, will have the looping line located on the bottom of the foot which is considered desirable as it gives a toe without any seaming except for the looping line underneath the toe. If it is desired to make the circumference of the stocking 10 at the base of the toe slightly less than the circumference of the stocking adjacent the heel, this can be done by causing the sole portions 4' to be gradually widened from the toe thus fashioning the foot D' of the stocking A' and fashioning the adjacent part of the leg B of the stocking A. Where this is done the needles on which the heel 12' is made will not only include the needles used in forming the sole portions 4' of the stocking A' which are thrown out of action when making the toe pocket 6', but will include 15 some of the needles used for the leg portion B of the stocking A after the toe pocket 6' was knit. Where the reinforcing yarn is used the reinforcing yarn will be fed to some of the needles used in forming the leg B of the stocking A as the heel 12' is approached and the fabric so reinforced will become part of the foot D' when the stockings are cut and seamed, the needles to which the reinforcing yarn is fed being selected in the usual way. The heel pocket is made 20 in two parts either by knitting half heel pockets by the ordinary narrowed and widened method or by knitting tabs 12' which are cut and looped to the stocking foot to form halves of a square heel. In each case the other needles in the machine are idle while the heel pockets or tabs 12' are being knit by reciprocating knitting.

After the heel portions have been knit the knitting proceeds by round and round method, the leg B of the stocking A being knit towards the foot while the leg B' of the stocking A' is knit towards the welt. When the proper points are reached the heel of the stocking A and the toe pocket 6 thereof are knit in the reverse order to that described, the sole portions 4 reinforced if the sole portions 4' were reinforced, being provided between the heel and the toe pocket 6. As shown in Fig. 2 the needle segments for knitting the heel and toe of stocking A are diametrically opposite those used for stocking A'. After the completion of the toe pocket 6 the welt W' of the stocking A' is knit by round and round knitting 30 as in the case of the welt W.

In the knitting of the blank it may be found desirable to indicate the line C on which the stockings are to be separated which may be done by a row of tuck or drop stitches. The line C, it will be noted, indicates the place of separation between the feet D, D' and the leg portions B' and B, respectively, as well as between the leg portions B and B'. When the stocking blank is taken from the machine in order to have the seams at the back of the stocking come on the inside of the finished stocking, the blank is turned inside out and if an automatic welt machine has 35 not been used the welts are turned. With the

blank turned inside out two lines of sewing are run along the line C forming the seam at the back of each stocking and the stockings are separated along the line C producing a neat seam without irregularities or missed stitches. The sewing of both stockings and separating them along the line C may be performed simultaneously. The stockings are then ready to have the heels and toes seamed. While it is possible to loop the toe and seam the heel before the two stockings are separated, it is believed preferable to do this after the stockings are separated. In the case of the toe, the looping is done in the ordinary manner for seamless stockings which are looped on the bottom of the foot. In the case of the heel if the two tabs 12' are formed the tabs are cut and one edge of each tab adjacent to the sole of the foot is looped to the wales of the fabric of the sole and the two tabs are looped together forming the bottom of the heel in the same manner as the heel tabs of the ordinary full fashioned stocking are looped together. The edges of these tabs may be sewed or looped together thus closing the heel. Where the separately formed heel and toe are used they will be looped to the foot portion in the usual manner. 40

I claim—

1. A blank for manufacturing stockings comprising a knit tube forming oppositely disposed leg portions arranged side by side and foot portions, and heel portions forming folds attached to said tube adjacent said leg portions. 45

2. A blank for manufacturing stockings comprising a knit tube forming oppositely disposed leg portions arranged side by side and foot portions, including reinforced sole portions, and toe and heel portions forming folds attached to said tube adjacent a portion of said leg portions. 50

3. A blank for manufacturing stockings comprising a knit tube having top portions at opposite ends thereof, oppositely disposed leg portions placed side by side extending from said top portions, foot portions having instep portions separated from opposite leg portions by reinforced sole portions and toe and heel portions projecting from said foot portions. 55

4. A blank for manufacturing stockings comprising a knit tube having top portions at opposite ends thereof, oppositely disposed leg portions extending from said top portions and having their seam portions adjacent, each leg portion being extended to form foot portions comprising instep portions separated from the other leg portion by sole portions and toe and heel portions joined to said foot portions and forming folds attached to said tube. 60

5. In the method of manufacturing stockings the steps which comprise knitting a tube of sufficient diameter for two oppositely disposed stockings placed side by side and knitting oppositely disposed heels and toes as folds attached to said tube in the length thereof. 65

6. In the method of manufacturing stockings the steps which comprise knitting a tube of sufficient diameter for two stockings, knitting partial courses to form heel and toe portions as folds having the ends of each fold connected to adjacent complete courses of the tube, uniting opposite sides of the tube to form two stockings and separating the stockings. 70

7. In the method of manufacturing stockings the steps which comprise knitting a tube of sufficient diameter for two stockings, knitting toe and heel portions as folds adjacent the ends of the 75

- tube, uniting opposite sides of the tube to form two stockings and separating the stockings.
8. In the method of manufacturing stockings the successive steps which comprise knitting a 5 welt, knitting a toe pocket, simultaneously knitting a leg portion, two reinforced sole portions and an instep portion, knitting a heel portion, knitting two leg portions and then carrying out the previous operations in the reverse order.
- 10 9. In the method of manufacturing stockings the successive steps which comprise knitting a welt, knitting a toe pocket, simultaneously knitting a leg portion, two sole portions and an instep portion, knitting a heel portion, knitting two 15 leg portions simultaneously and then carrying out the previous operations in the reverse order.
- 10 10. In the method of manufacturing a stocking, the successive steps which comprise knitting a welt, knitting a toe pocket adjacent the welt, 20 simultaneously knitting a leg portion, two sole portions and an instep portion joined to the welt and toe pocket, knitting a heel portion joined to the sole portion, knitting two leg portions simultaneously and then carrying out the previous 25 operations in the reverse order.
- 11 11. In the method of manufacturing stockings, the steps on a circular knitting machine which comprise knitting a welt on all the needles, knitting a toe pocket on a segment of the needles, 30 knitting a stocking leg portion, two reinforced sole portions and an instep portion on all the needles, knitting a heel portion on a segment of the needles, knitting two leg portions upon all the needles and then carrying out the previous 35 operations in the reverse order.
- 12 12. In the method of manufacturing stockings, the steps of forming a blank on a circular knitting machine comprising knitting a welt on all the needles, knitting a toe pocket on a segment of the 40 needles while the rest are inactive, knitting a stocking leg portion, two sole portions and an instep portion on all the needles, knitting a heel portion on a segment of the needles while the remaining needles are inactive, knitting two leg 45 portions upon all the needles and completing the blank by carrying out the previous operations in the reverse order.
- 13 13. In the method of manufacturing stockings the steps of forming a blank on a circular knitting 50 machine, comprising knitting a welt on all the needles by round and round knitting, knitting a toe pocket on a segment of the needles by recipro-
- cating knitting while the remainder of the needles are inactive, knitting a stocking leg portion, two reinforced sole portions and an instep portion by round and round knitting on all the needles, knitting a heel portion on a segment of the needles by reciprocating knitting while the remainder of the needles are inactive, knitting two leg portions on all the needles by round and round knitting and completing the blank by carrying out the previous operations in the reverse order.
14. In the method of manufacturing stockings the steps which comprise knitting by rotary knitting a tube of sufficient diameter to form the legs and portions of the feet of two oppositely disposed stockings placed side by side and knitting by reciprocating knitting oppositely disposed heel and toe portions as folds attached to the tube.
15. In the method of manufacturing stockings, the steps on a circular knitting machine which comprise knitting a welt on all the needles, knitting a toe pocket on a segment of the needles while the rest are inactive, knitting a stocking leg portion, two sole portions and an instep portion on all needles, knitting spaced heel portions 100 on spaced segments of the needles, knitting two leg portions and a high splice portion on all the needles, knitting two leg portions on all the needles and then carrying out the previous operations in the reverse order.
16. In the method of manufacturing stockings, the steps which comprise knitting a tube of sufficient diameter for two stockings placed side by side with the foot of one stocking adjacent the leg of the other stockings and having heel and 110 toe portions joined to said tube, uniting the opposite sides of the tube along a substantially diagonal line passing adjacent the heels to form two stockings and separating the stockings and completing the joining of the heel and toe with 115 the foot portions.
17. In the method of manufacturing stockings the steps which comprise knitting a tube of sufficient diameter for two stockings, knitting toe and heel portions as folds attached adjacent the ends 120 of the tube and projecting from the body of the tube, uniting opposite sides of the tube along a substantially diagonal line passing adjacent the heels to form the legs of two stockings, separating the stockings and completing the joining of the 125 toe and heel portions to the body of the stocking.

CERTIFICATE OF CORRECTION.

Patent No. 1,942,331.

January 2, 1934.

JAMES L. GETAZ.

It is hereby certified that error appears in the printed specification of the above numbered patent requiring correction as follows: Page 1, line 62, after the word "shown" and before the period insert the words with the foot of one stocking adjacent the leg portion of the other; page 2, line 22, after "toe" insert into the leg portion B of the stocking A; line 32, strike out the article "the" first occurrence, and lines 32 and 33, strike out the words "the reinforcing yarn" and insert instead the word it; and that the said Letters Patent should be read with these corrections therein that the same may conform to the record of the case in the Patent Office.

Signed and sealed this 6th day of February, A. D. 1934.

F. M. Hopkins
